UNITED STATES PATENT OFFICE.

JOSEPH DETRIK, OF PRICEDALE, PENNSYLVANIA, ASSIGNOR OF ONE-THIRD TO JOHN KOMLÓSI, OF PRICEDALE, PENNSYLVANIA.

EXTENSION-LADDER.

1,112,122.

Specification of Letters Patent. Patented Sept. 29, 1914.

Application filed December 2, 1913. Serial No. 804,151.

To all whom it may concern:

Be it known that I, JOSEPH DETRIK, a subject of the King of Hungary, residing at Pricedale, in the county of Westmoreland 5 and State of Pennsylvania, have invented certain new and useful Improvements in Extension-Ladders, of which the following is a specification.

This invention relates generally to extension ladders, and more particularly to one of that type employed by fire engine companies in reaching the windows of high buildings.

The object of the invention is to provide 15 an apparatus of this character embodying in its construction, an extensible ladder, and an endless traveling carrier combined with the ladder and equipped with safety devices in the nature of belts or pouches to receive 20 persons escaping from the burning building, and for conveying them to a point adjacent to the ground.

A further object of the invention is to provide an apparatus of this character in 25 which the parts shall be so constructed and assembled as to render them adjustable to be raised to reach the windows of buildings of extra height, the arrangement of the parts being such that, with a small amount 30 of labor, and with readiness and ease, the extra parts necessary to meet an unexpected contingency, may be brought into use, and be rendered effective in the shortest possible space of time.

35 A further object of the invention is to provide an apparatus of the character as stated embodying an extensible ladder, and means for elevating the same, and an endless carrier provided with safety appliances in the nature of belts or pouches, combined with means operating simultaneously, but independently, to elevate the ladder and drive the belt or conveyer.

With the above and other objects in view, 45 as will appear as the nature of the invention is better understood, the same consists, generally stated, in an apparatus of the character stated embodying a plurality of hingedly connected ladders, each including 50 two sets of rungs between which latter, and on each section of the ladder is disposed an endless belt or carrier, carrying safety appliances, means being employed for transmitting motion, from a source of power 55 through the series of belts simultaneously

with means for elevating the sections of ladder carrying the belts, and for maintaining the extended ladder at the desired height. In addition, means is provided, whereby as it becomes requisite to lengthen the ladder, 60 the elevating means therefor will be rendered capable of similar extension, so that within prescribed limits, the ladder may be elevated to reach any desired window in a building.

65 The invention consists further in the various novel details of construction of an extension ladder, as will be hereinafter fully described and claimed.

In the accompanying drawings, forming 70 a part of this specification, and in which like characters of reference indicate corresponding parts: Figure 1 is a view in side elevation of a combined extension ladder and fire escape constructed in accordance 75 with the present invention, the upper portion of the structure having its parts displayed in the position they will assume when the apparatus is used as a fire escape. Fig. 2 is a similar view, partly in section, 80 showing the upper portion of the structure having its parts displayed in the position they will assume when the apparatus is used by firemen in playing streams of water upon a burning building. Fig. 3 is a view 85 in front elevation. Fig. 4 is a view in rear elevation. Fig. 5 is an enlarged detail view in perspective of the upper portion of the apparatus. Fig. 6 is a similar view of a portion of one of the ladders and the endless belt or conveyer. Fig. 7 is a detail view 90 in elevation, on an enlarged scale, showing a portion of the mechanism for actuating the racks that elevate the ladders. Fig. 8 is a sectional detail view of a portion of the 95 rack elevating mechanism. Fig. 9 is a detail view, in side elevation, showing one means by which two of the elevating racks may be connected.

The base of the apparatus, as shown in 100 Figs. 1, 2, 3, and 4, comprises two longitudinal sills or beams 1, preferably of metallic eye-beams, connected and braced by a terminal metallic eye-beam 2, of which any preferred number may be employed, thus to 105 provide a frame-work that will not only be rigid in character, but possessing the requisite fire-proof qualities. Depending from the sills 1 are two bearings 3 in which is journaled a shaft 4 carrying supporting 110

wheels 5, which are arranged at the front of the frame, and support the ladder at this point, the rear ends of the frame being supported by a pair of wheels 6, smaller than the front wheels, and working upon an axle 7 journalized in hangers 8 depending from side sills and rotatably connected therewith by a king-bolt 9, a lever 10 secured at one end intermediate of the length of the axle 7 and extending forwardly and provided with an upstanding hand grip 11, Fig. 1, serving as a guiding means for the apparatus when being propelled over a street or a road.

The motor 12, diagrammatically shown, 15 may be of any type, preferably one that is driven by gasoline, the drive shaft 13 having connected to one end a sprocket wheel 14, around which passes a sprocket chain 15 that engages a sprocket wheel 16 on the 20 shaft of the wheels 5, and it is through these sprocket wheels and the chain that motion is imparted to the apparatus from the engine. It is to be understood, of course, that suitable valve gearing will be provided for 25 controlling the action of the engine, and as this may be of the usual or any preferred construction, and forms no part of the present invention, illustration thereof is omitted.

One of the essential features of the present invention resides in the novel form of 30 sectional ladder, a detailed view of which is shown in Figs. 5 and 6. It is to be understood that any desired number of sections may be employed and that each section will 35 be a counter-part of the other, so that a description of one will serve for all. As shown in Fig. 5, each section comprises two exterior side bars 17 and four interior side rails 18, 19, 20, and 21, the bars and series of rails 40 being connected and rendered rigid by cross braces 22, that are preferably mortised into the bars 17, as clearly shown in Fig. 6, the pairs of rails 18 and 19, and 20 and 21 being connected by rungs 23, the rails 18 and 19 45 with their rungs constituting one ladder and the rails 20 and 21 with their rungs 23 constituting a second ladder, the two ladders being spaced apart to form a run-way for an endless traveling belt or conveyer 24, 50 which may be constructed of any suitable material, such as leather or canvas, and carries a safety appliance in the nature of a pouch or bag 25 to receive a person escaping from a building, and a second safety appliance 55 26 in the nature of a belt, by which the person may strap himself or herself to the belt. Extending through each of the two bars of each ladder section adjacent to its upper and lower ends are transverse shafts 60 27, more clearly shown in Fig. 6, and each of these shafts, at each end, carries two sprocket wheels 28 and 29 respectively, the pairs of sprocket wheels 29 being engaged by sprocket chains 30 that pass around complementary sprocket wheels 29^a on the next

adjacent shaft 27 the pairs of sprocket wheels 28 being engaged by sprocket chains 31 that pass around sprocket wheels 32 carried by a transverse shaft 33 at the upper end of the topmost ladder section. The conveyer or endless belt 24, is secured at its edges to sprocket chains 35, the belt extending throughout the entire length of the series of ladders, and the chains 35 engage at their lower ends with sprocket wheels 36 carried by a shaft 37 mounted in standards 38 secured to the base of the structure as shown in Fig. 2. The terminals of the shafts 27 are journalized in plates 39 arranged exteriorly of the bars 17 adjacent their meeting ends, and each of these plates carries a shaft 40 supporting at its inner end a roller or wheel 41, these wheels being designed to bear against the sprocket chains to prevent any undue flapping of the belt. The sprocket wheel 36 is driven by a sprocket chain 42 that passes around a sprocket wheel 58^a mounted on a shaft 58^b, the latter carrying a second sprocket wheel 59 that is engaged by a sprocket chain 71^x that passes around a sprocket wheel 73 on a shaft 69, the latter being driven in any suitable manner from the engine, and thus imparts motion to the belt. In order to retain the ladder sections rigid, relative to the other when 95 extended, each bar carries on each side a keeper 43 that is engaged by a latch 44 which may readily be inserted or removed.

Supported at one end upon a rod 44^a secured in the upper end of the topmost ladder section is a platform 45, the other end of which is supported by adjustable rods 46 from the ladder to maintain the platform in horizontal position irrespective of the inclination of the ladder. This platform is 100 provided with a railing 47, and with a hinged bottom 48, which when thrown into the position shown in Figs. 1 and 5, will permit persons to escape from a building, either to pass down the ladders, or to utilize 105 the endless conveyer, the platform 48 when moved to the position shown in Fig. 2 serving as a flooring to permit the fireman to have a solid base on which to stand while employing a hose. In addition, there is a 110 hook 49 provided which may be secured over a window sill, or any other projecting part of a building, thus to hold the structure in convenient position to be reached by the persons desiring to use it. If desired, and as 115 will generally be preferred, the bars 17 will be provided with hooks 50 to support the hose while the fireman is climbing to the platform.

The means for distending the ladder sections to bring the platform to the desired height comprises a plurality of racks which are adapted to be connected so as to utilize the full length of the ladder. As shown in Fig. 2, two of these racks 51 and 52 are con- 120

nected by the lapped joint 53 (Fig. 9) and connected by bolts 54, this being one means of accomplishing the result desired. The lowermost rack 52 engages one of a series of 5 sockets 55, carried by a sprocket chain 56 engaging the sprocket wheels 57 and 58, other racks 59 and 60 to be used in an emergency, being supported by other sockets on the sprocket chain 56. This chain may be 10 manually driven by a crank 61 carried by the shaft of a sprocket chain 57 and operating the latter.

Supported upon the base of the structure is a channeled upright 62 in which a portion 15 of two of the racks is housed, the upper portion of the standard or upright carrying gear wheels 63 and 64, the shaft of the latter having connected with it a series of curvilinear spring arms 65 that bear against the 20 back of the topmost rack and serve to hold rack 51 has connected to its upper end two arms 66, and to these are pivotally connected the lower ends of two arms 67, the upper ends of which are pivotally connected to the 25 outer sides of the bars 17. The shafts 68 and 69 of the gears 64 and 63 are journaled in uprights 70 supported by the base of the apparatus, the shaft 69 carrying at its terminals, exteriorly of the standards 70, two 30 sprocket wheels 71, and interiorly of the standards a gear wheel 72, that meshes with the gear 64 and a sprocket wheel 73 that is engaged by a sprocket chain 74 driven directly from the engine. The sprocket 35 wheels 71 are loose on the shaft 69, but may be held in locked relation thereto by means of pawls 75 secured externally of the standards 70 and arranged to engage with ratchet wheels 76 rigid with the sprocket wheels 71. 40 The arrangement of these pawls and ratchet wheels is such that when the engine is operated to lift the rack bars through the gears 63, the sprocket wheels 71 will be fixed with relation to the shaft 69, but when it is desired to lower the racks for the purpose of 45 disposing the ladder sections upon the platform, the pawls will slip over the ratchet wheels for this purpose. Each of these pawls has connected with it a lever 77 (Fig. 50 1). The object of this lever is to permit the operator to throw the pawls out of engagement with the ratchet wheels when so desired.

As will be obvious, some means must be 55 provided whereby the racks shall be held in raised position, and that herein shown consists of a bell crank lever 78 is pivotally supported to the uprights 62 and has one of its arms arranged to project through an opening 79 in the upright and to engage with the rack, a lever 80 being provided with which connects one end of the rod 81, the other end of which is secured to the bell crank lever. The lever carries a spring- 60 65 pressed latch 80^a that is arranged to be

thrown into and out of engagement with a rack 80^b, thus to lock the bell crank lever relative to the rack.

In operation, assuming that the parts be 70 in the position shown in Fig. 2 and it be desired to extend the ladder to bring the platform into a more elevated position, the engine will be started and the racks will be raised by the gears 63 until the lower end of the rack 52 has reached a pre-determined point. During this action, the endless carrier has also been extended to compensate 75 for the addition in the length of the ladder. The crank 61 is now operated to actuate the sprocket chain 56 and thus bring the next succeeding rack 60 into position to be coupled with the rack 52, the same operation being repeated with regard to the rack 59. It will be understood that when the ladder sections are folded to the position in which 80 two of them are shown in Fig. 2, that the endless carrier will lie in between the latter sections, and as this will readily be understood, the belt is omitted in Fig. 2 for clearness of illustration.

It is to be understood of course, that the invention is not to be limited to the number of racks shown, as a greater number than that illustrated may be employed.

It will be seen from the foregoing description that by the apparatus disclosed, that not only may persons be rescued from a burning building, but also that the work of the firemen will be materially assisted, and further that within certain limits, the apparatus may 95 be used in connection with a building of any 100 height.

I claim:

1. A structure of the class described, comprising a plurality of pivotally-connected 105 ladders, a rack bar connected with the uppermost ladder of the series, means coacting with the rack bar to lift the series of ladders, an endless traveling carrier associated with the series of ladders, and means for 110 imparting motion to the carrier.

2. A structure of the class described, comprising a wheeled platform, a series of pivotally-connected ladders supported thereby, one of which is permanently assembled with 115 the platform, an extensible rack bar connected with one end of the uppermost series of the ladders, means for imparting vertical movement to the rack bar whereby to elevate the series of ladders, an endless carrier disposed between the side rails of the ladders, and means for imparting movement to the carrier longitudinally of the ladders.

3. A structure of the class described, comprising a wheeled platform, a series of pivotally-connected ladders disposed upon the platform, one of which is permanently combined therewith, a platform carried by the upper end of the uppermost ladder of the series, means for maintaining the latter plat- 120 125 130

- form in horizontal position irrespective of the inclination assumed by the ladder, a rack bar operatively connected with the latter ladder, means for imparting an upward movement to the rack bar to raise the series of ladders, an endless carrier disposed between the side rails of the ladders, means for imparting longitudinal traveling movement to the conveyer, and means carried by the conveyer to accommodate a person using the appliance.
4. A structure of the class described, comprising a wheeled platform, a series of ladders disposed thereon, one of which is permanently connected with the platform, a platform supported by the upper end of the uppermost of the series of ladders, means for adjusting the latter platform relative to the ladder whereby to cause it to maintain a horizontal position irrespective of the inclination of the ladder, means carried by the

platform for holding the ladder connected with a window frame, a rack bar connected with the upper end of the uppermost ladder, means for imparting vertical movement to the rack bar, and a traveling conveyer carried by the sections of the ladder and disposed between the side rails thereof.

5. A structure of the class described comprising a series of pivotally connected spaced foldable ladders, an endless traveling belt interposed between the series and foldable therewith, means for imparting movement to the belt, and means for elevating the ladders independently of the belt driving means.

In testimony whereof I affix my signature in presence of two witnesses.

JOSEPH DETRIK.
